CUP FEED SEWING MACHINE

Martin L. Cook, Western Springs, Ill., assignor to
Union Special Machine Company, Chicago, Ill.,
a corporation of Illinois

Application June 5, 1951, Serial No. 230,026

20 Claims. (Cl. 112—20)

1

This invention relates to uncurler guides of the type used on cup feed sewing machines employed in the seaming of hosiery and the like. These are adapted to support and guide the work as it is fed into the bite of the feed cups; they serve also to uncurl the selvedges of the knit blank to present them in flattened condition to the stitch forming devices which produce an overedge seam along the butted edges. Normally the blanks are seamed in such a way as to place the seam on the inside of the finished stocking, the latter being turned inside-out after seaming. In this conventional or standard method the selvedges tend to curl outwardly when the blank is applied to the uncurler. Sometimes, however, the blank is seamed to provide the seam on the outside of the stocking and in such cases the selvedges are arranged to curl inwardly as the blank is applied to the uncurler. An inside-out uncurler is then required. The present invention is applicable to both types of uncurler guides.

As heretofore constructed the work holding and guiding surfaces of the uncurler have terminated some distance forwardly of the bite of the feed cups so that it has been necessary for the operator to grip the end of the work just below the feed cups and pull it toward the bite of the latter in commencing a seaming operation on a new piece of work. It will be understood that in the seaming of full-fashioned hosiery the seam is started at the toe end of the blank and is formed along the bottom of the foot portion, then around the heel and then upwardly along the back of the leg portion. In pulling the toe portion of the blank into the bite of the feed cups, as explained, it has been found that variable results are produced as a result of the human factor involved in gauging the correct amount of force to be employed by the operator and in determining the correct point for the commencement of the seam. The thinness and stretchability of the material have made the production of uniform results extremely difficult. Frequently "drop outs" have occurred as a result of improper feeding of the work into the bite of the feed cups and pleating or other defects have occurred from the improper commencement of the seam.

In the use of the invention in connection with hosiery blanks which have been looped, uniform starting of the seam in relation to the loop line is insured. The tendency, which existed heretofore, of starting the seam too far ahead of the loop line, because of an upward pull on the toe of the blank as the operator has pulled it into the bite of the feed cups, has been eliminated.

2

The invention is also highly advantageous in connection with the seaming of loopless toe hosiery, interest in which is being revived because of the shortage of loopers and skilled operators therefor. It will be understood that loopless toe hosiery is produced without the necessity of a looping operation between the knitting of the blank and the formation of the seam along the foot and the back of the leg portion of the stocking. In the knitting of the blank the selvedges at the toe end are brought together along inwardly sloping lines to the base of a relatively narrow tip which is then formed by a short extension of the selvedges of the blank. As the blank is seamed to form a full-fashioned stocking, the tip is folded back into the foot of the stocking at the toe end and is incorporated in and concealed by the overedge seam. Unless due care is exercised, the pulling action by the operator, in the use of machines as previously constructed, has been found to pull the edges to be seamed out of position, with resultant drop-outs at the start of the toe.

An important object of the present invention has been to so construct and arrange an uncurler guide for cup feed machines of the type employed in the seaming of hosiery that it enables the work blank to be presented to the feed cups in a definite predetermined manner with a minimum of effort and exercise of skill and judgment on the part of the operator. The invention thus insures the production of uniform results in the seaming of hosiery blanks and the like without the exercise of extreme care and skill by the operator. Drop outs and other difficulties and defects are reduced to a minimum.

A further object of the invention, in its preferred form, has been to so construct and arrange the work guide and uncurler and related parts as to eliminate completely the necessity of manual pulling and feeding of the toe end of a hosiery blank into the bite of the feed cups. The arrangement is such that the blank may simply be applied to the uncurler in the conventional manner, while the latter is in its loading or work applying position, and the blank is then automatically introduced into the bite of the feed cups in a definite, predetermined manner by the simple movement of the uncurler into its operative position, without the necessity of any further effort or the exercise of any special skill by the operator.

In attaining the foregoing objects, the invention involves a novel construction of the uncurler guide and the modification of various cooperating members to insure the proper introduction

of the work at all times into the bite of the feed cups. Drop-outs, pleating and other difficulties and defects are thus substantially eliminated.

Another object has been to so construct certain needle guarding and stitch finger means, associated with the feed cups and stitch forming devices, as to facilitate the proper delivery of a stocking blank to the stitching point.

Other objects, features, and advantages of the invention will appear from the detailed description of a preferred embodiment of the same, and certain suggested variations which will now be given in conjunction with the accompanying drawings, in which:

Fig. 1 is a front elevational view of the upper portion of a cup feed sewing machine embodying the invention, certain parts being broken away;

Fig. 2 is a horizontal sectional view through the feed cup supporting structure, taken just above the stitch finger and looking down upon the feed cups;

Fig. 3 is a view similar to Fig. 2 with the stitch finger removed;

Fig. 4 is a side elevational view of the uncurler guide of the invention shown in its operative relation to the inner feed cup;

Fig. 5 is a detail view showing the lower portion of the uncurler guide with a work piece applied thereto;

Fig. 6 is a detail view showing the lower portion of the uncurler guide in operative position in relation to the inner feed cup, with the stitch finger shown in section;

Fig. 7 is a detail view, partly in elevation and partly in vertical section, showing the outer feed cup and the needle guard mounted therein;

Fig. 8 is a bottom view of a stitch finger which may be employed in connection with the invention;

Fig. 8a is a bottom view of a modified form of stitch finger which may be employed;

Fig. 9 is a front elevational view of the uncurler guide in operative relation to portions of the feed cups;

Fig. 10 is a detail view, in perspective, of a stitch finger supporting structure;

Fig. 11 is a fragmentary view of the toe end of a loopless toe hosiery blank opened out;

Fig. 11a is a fragmentary view of the toe portion of the hosiery blank folded together and with an overedge stitch applied to the edges thereof;

Fig. 12 is a side view of the lower portion of the center plate of the uncurler;

Fig. 13 is a view similar to Fig. 5 showing a modified form of uncurler guide adapted for inside-out uncurling;

Fig. 14 is a detail view, in side elevation of the modified uncurler guide of Fig. 13, a part being broken away;

Fig. 15 is a front elevational view of the modified uncurler guide; and

Fig. 16 is a bottom plan view of the modified uncurler guide.

The invention has been illustrated as applied to a cup feed sewing machine of the general type disclosed in the patents to Rubel, et al. No. 2,043,711, granted June 9, 1936, Hacklander No. 2,043,748, granted June 9, 1936, and Hacklander No. 2,043,749, granted June 9, 1936.

Referring to Fig. 1, the machine comprises a main frame 10, having an upwardly extending standard adapted to be supported by a table and having at its upper end a laterally extending bracket arm 11. A horizontally disposed main

operating shaft 12 extends from front to rear of the vertical standard and is provided at its two ends, which project through the front and rear walls of the frame, with combined hand-wheels and pulleys 13 through which power may be supplied for the operation of the machine. Since the operating mechanism, the stitch forming devices and the means for supporting and driving the feed cups do not form a part of the novel construction to be claimed herein, these portions of the machine will be but briefly described.

The stitch forming devices include a reciprocating needle bar 14 disposed horizontally and arranged for reciprocation within a bearing sleeve 15 extending through a wall of the main frame. A needle 16 is suitably mounted on the needle bar for reciprocation across the tops of the feed cups to be hereinafter described. Cooperating with the needle in the formation of over-edge stitches is a thread carrying looper (not shown) carried by a reciprocating and oscillatory shaft or bar 17 mounted for sliding and rocking movements in an inclined bearing sleeve 18 which extends through a wall of the frame. A spreader (not shown) cooperates with the looper and the needle in the formation of the stitches and this is mounted for oscillation with a rock shaft 19, parallel with the shaft 17 and journalled in a bearing sleeve 20 extending through a wall of the machine frame. The arrangement and operation of the several stitch forming elements is such that a two-thread overedge stitch is formed. If desired, the spreader mounted on the shaft 19 may be replaced by a thread carrying looper, so that a three-thread overedge stitch will be formed. Reference may be had to the Rubel, et al, and Hacklander patents above mentioned for a fuller disclosure of the construction and operation of the stitch forming devices.

For advancing the work in relation to the stitch forming devices, a pair of feed cups 21 and 22 is provided. The upper portions of these feed cups are preferably in the form of serrated rims which cooperate and serve, upon intermittent rotation of the feed cups, to grip and advance the work. If desired, the rims of the feed cups may be provided with other forms of fabric gripping surfaces. It will be understood that the stitch forming devices serve to produce an overedge stitch just above the upper edges of the rims of the feed cups in the region of the bite of these cups. Feed cup 21 is secured to the lower end of a shaft 23 journalled in a sleeve 24, while feed cup 22 is secured to the lower end of a shaft 25 journalled in a bearing sleeve 26. The shafts 23 and 25 are arranged to be driven intermittently by connections from the main drive shaft 12 of the character disclosed in the above mentioned Rubel, et al. and Hacklander patents. Bearing sleeve 24 for the outer feed cup is arranged to be tilted outwardly in the manner disclosed in said patents for carrying the outer feed cup out of engagement with the inner feed cup to facilitate the introduction and removal of work. Puller means may be provided to assist the feed cups in advancing the work properly through and beyond the stitch forming zone. In Figs. 2 and 3 there is illustrated a puller of the character disclosed in Figs. 8 and 9 of the patent to Cook No. 2,448,774, granted September 7, 1948. It comprises a plate-like member 27 carried by an arm 28 which is urged by a spring 29 to yieldingly press the puller plate against the periphery of the outer feed cup.

Other puller means than that disclosed may be employed, if desired.

Within the outer feed cup 21 there is mounted a needle guard 30 having a passage 30a aligned with the needle 16 for receiving and guiding the latter in the course of its reciprocation. This needle guard is secured by screws 31 to a radially extending flange 32 at the lower end of the bearing sleeve 24. Reference will be made herein-after to certain novel details of construction of this needle guard.

A lug 33 which extends downwardly from the bracket arm 11, in the region of the shaft 25 (Fig. 1), is arranged to support the structure illustrated in Fig. 10. The latter comprises an angle member 34 having elongated openings 35 for receiving screws (not shown) by which the angle member may be adjustably secured to the lug 33. To the under side of the angle member 34 there is secured a slide 37 by means of screws 38. This provides for slight adjustment toward and away from the shaft 25. Slide 37 has a downwardly extending part 39 provided in its forward face, adjacent its lower end, with a channel which receives a shank portion 40 of a needle guard and stitch finger supporting member 41. The shank 40 is adapted for slight longitudinal adjustment in the channel and is secured in desired position by a screw 42. The outer end of member 41 is of arcuate form, corresponding with the curvature of the rim of the feed cup, and has a radially projecting flange 43 which extends over the top of the rim of the inner feed cup. This flange, however, terminates slightly inwardly of the outer periphery of the rim. A finger-like extension 44 of member 41 projects rearwardly beyond the line of reciprocation of the needle and is provided with a notch or groove 45 for the passage of the needle. Screws 46 (Fig. 2) cooperating with threaded openings 46a (Figs. 3 and 10) serve to secure a stitch finger 47 to the member 41. This stitch finger may be of the type shown in detail in Fig. 8, or it may be of the modified form shown in Fig. 8a. It is provided with a pointed finger 48 disposed directly above the rims of the feed cups along the line of feed of the work through the bite of the feed cups. As will be understood, the over-edge stitches are first formed about the finger 48 and are fed off of the finger as the work progresses.

Referring particularly to Figs. 1 and 4, there is shown the means for supporting the novel uncurler guide forming an important part of the invention. This is mounted on the overhanging bracket arm of the machine frame in any suitable way. In the drawings the uncurler is illustrated as being mounted in accordance with the teachings of the patent to Kucera No. 2,292,762, granted August 11, 1942. For full details as to the mounting of the uncurler, reference may be had to said Kucera patent and also to the patent to Hacklander No. 2,131,007, granted September 20, 1938. Briefly, the mounting means comprises a vertically movable slide 50 retained by a pair of gibs or guide elements 51 and 52 secured to the forward face of the frame. The slide and the guide elements may suitably be formed with complementary bevelled surfaces. A spring 53 (Fig. 4) normally urges the slide downwardly until the lower face of a knurled nut member 54 engages the top of a stop finger 55 secured to the frame. Member 54 may be adjusted to any desired position along a screw stud 56 projecting upwardly from the slide 50 and thus predetermining the normal position of the slide and the parts carried

thereby. As shown in Fig. 1, the member 54 may suitably be provided with indicia cooperating with an index mark on the finger 55 to indicate the normal position of the slide 50. The slide 5 may be lifted against the action of the spring 53 under the control of the operator of the sewing machine. For this purpose, a lever 57 pivoted at 58 on the frame is adapted to be rocked clockwise by a downward pull on a chain 59 or other connection from a foot treadle or knee press. At its opposite end the lever is slotted to cooperate with a screw 60 projecting from the slide 50. Rocking of the lever 57 in a clockwise direction will therefore cause lifting of the slide 50. 10 A knurled nut 61 adjustably mounted on the screw stud serves to limit the extent of upward movement of the slide in response to operation of the treadle or knee press. As disclosed in the Kucera patent above mentioned, a ball detent or the like may be provided to prevent accidental displacement of the nut 61. It will be understood that the lifting of the slide, by the operation of the lever 57, will normally be made to take place as the heel portion of the stocking blank is brought to the stitching point. This is for the purpose of forming a somewhat deeper seam around the heel portion of the stocking.

The lower end of the slide 50 carries a split clamping collar 62 adapted to receive and retain 30 a bearing sleeve 63 which serves to support a rock shaft 64 having a detent controlling arm 65. Between the shaft 64 and the bore of the sleeve 63 is mounted a hollow rock shaft 66 to one end of which is secured a hub 67 of an uncurler support. 35 A downwardly extending flange 68 integral with this hub is formed with a transverse channel arranged to receive a rib 69 on a central support member 70 of the uncurler. A pair of screws 71 may be provided to secure the member 70 to the extension 68. The arrangement is preferably such that member 70 may be adjusted slightly in a direction toward and away from the bite of the feed cups. To the lower end of the member 70 there is secured, by welding or the like, a center plate 72, certain details of which will be herein-after described. The lower end of member 70 is also provided with laterally extending ears or bosses 73 which provide bearings for pins 74 carrying clamping elements 75 and 76 of the uncurler. These clamping elements have, at their lower ends, work-engaging or boot portions 77 and 78 arranged to hold the upper edges of the work blank against the opposite faces of the center plate 72. A spring 79, passing through an opening in the member 70 and seated at its opposite ends in pockets formed in the elements 75 and 76, serves to urge these elements yieldingly into the position indicated in Figs. 1 and 9. A guide pin 81, which may suitably be formed as two interconnected, screw-threaded parts, is secured to the center plate 72 and projects laterally therefrom at both sides through cooperating openings provided in the work engaging portions 77 and 78 of the clamping elements. As will be understood, the guide pin 81 serves to locate the line of movement of the upper edges of the work.

Referring now to Fig. 4, which illustrates an uncurler having the conventional action, the boot portion 77 of the clamping element 75 is provided with an inclined upper edge 82 of a form adapted to produce the desired uncurling action. Its surface is preferably of a scalloped configuration and slopes downwardly at a slight angle from the surface of the center plate 72 toward the outer face of the boot 77. Boot 78 is of similar form.

The main body of center plate 72 preferably extends rearwardly beyond the rearmost edges of the clamping boots 77 and 78. As an important feature of the present invention, the center plate is provided with rearwardly extending prongs 83 and 84 (Figs. 4, 5 and 6), the prong 83 being slightly below the rims of the feed cups and the prong 84 being slightly above such rims. In the preferred construction as shown, the prong 83 is somewhat longer than the prong 84 and extends to a point in or beyond the vertical plane containing the line of reciprocation of the needle. It thus extends substantially to or beyond the bite of the feed cups. The upper prong 84, on the other hand, preferably terminates slightly in advance of the plane indicated to avoid interference with the needle. As shown in Fig. 6, the prong 84 is positioned substantially midway between the upper surface of the feed cup and the under face of the stitch finger 47.

While the particular form and relationship of the prongs 83 and 84 described above is preferred, it should be understood that at least some of the advantages of the invention will be derived if other relationships are adopted. For example, the two prongs may be of the same length, or, if desired, the upper prong may be slightly longer than the lower prong. It is of primary importance that the form of the keel of the center plate be such as to present the stocking blank as closely as possible to the bite of the feed cups when the uncurler guide is in its normal operative position. This is definitely insured by the provision of a prong 83 which extends substantially to the bite of the feed cups. In fact, due to the thickness of the material as held by the uncurler guide, gripping of the stocking blank by the feed cups will be insured even if the prong 83 terminates slightly in advance of the bite of the feed cups.

As is clearly set forth in the Hacklander patent above mentioned, the mounting of the uncurler guide is such that it may be readily shifted to, and retained in, any of three positions. It is illustrated in this case only in its operative position. It may, however, be shifted to an intermediate loading position or to an extreme upper position in which the stitch-forming devices will be made more accessible. When it is desired to apply a new stocking blank to the uncurler, it is shifted to the partially inclined or loading position indicated in Fig. XI of the Hacklander patent. Assuming that the invention is being used for the seaming of loopless toe-hosiery, the stocking blank will have its toe portion mounted on the uncurler in the manner shown in Fig. 11. Prior to its application to the uncurler, the blank 85 at its toe end will be in the form shown in Fig. 11. The selvedges 86 at the toe end of the blank converge toward each other and are then extended slightly to form a narrow tip or extension 87 which may suitably be about $\frac{1}{8}$ inches long and $\frac{1}{16}$ inch wide. This tip is disposed as indicated in Fig. 5 when the blank is applied to the uncurler. It will be understood that the uncurler is in the inclined loading position, rather than in the vertical position shown, when the blank is being applied. Upon the movement of the uncurler into its vertical operative position the feed cups will be able to grip the blank and advance its upper edge through the stitch-forming devices; there is no necessity for manual pulling of the blank into the bite of the feed cups. The uncurler may be swung into its operative position while the machine is running or while it is idle, according to the preference of the operator. As the blank is

advanced, the tip 87 will be folded forwardly, in passing beneath the stitch finger 48, into the plane of the selvedges. This occurs, at least in part, upon the movement of the uncurler into its operative position. A recess 88 provided in the bottom of the stitch finger facilitates the movement of the upper edges of the blank into the path of the stitch-forming devices. This may be accomplished to even better advantage by modifying the form of the under side of the stitch finger as shown in Fig. 8a. The groove 88a in this form is relatively wide throughout its length and is deeper than the recess 88 of Fig. 8. It will be understood that as the over-edge stitches 89 (Fig. 11a) are formed about the extension 87 of a loopless toe and the stitch finger 48, the extension will be incorporated in the seam.

To facilitate further the free passage of the upper edges of the work to the stitching point and to prevent curling of these edges into the path of the needle, various changes have been made in the construction of the needle guard and stitch finger supporting means. The needle guard 30, as best shown in Figs. 3 and 7, has been made to present its outer curved end along a line which is only a slight distance inwardly of the periphery of the rim of the feed cup 21. At the same time, that portion of the curved end of the guard which lies forwardly of the path of reciprocation of the needle has been relieved along its upper edge, as indicated at 30b. The relief is preferably in the form of a fillet or concave groove formed along the indicated portion of the edge. It may, however, be simply in the form of a bevel or similar type of relief. So also, the outer curved end of the support 41 for the stitch finger, i. e., the outer periphery of the flange 43 lies only slightly inwardly of the periphery of the rim of the feed cup 22, as best shown in Fig. 3. Moreover, the upper edge of the flange is relieved, as indicated at 43a (Figs. 3 and 10). This relief may be of the same character as described in relation to the relief 30b of the needle guard 30. In both instances the relief is of particular importance in the region just in advance of the point of stitch formation. The arrangement is such that adequate space is provided between the adjacent end surfaces of the needle guard 30 and the flange 43 of the support 41 to permit the projection or prong 84 of the center plate to extend to a point quite close to the path of reciprocation of the needle and to allow for the free movement of the upper edge of the hosiery blank up to the point of stitch formation. Beyond this point the curved end surfaces of the needle guard and stitch finger support are spaced only sufficiently, as shown in Fig. 3, to permit the free movement of the seamed portions of the selvedges. As indicated, the arrangement as a whole is such as to minimize the danger of curling of the selvedges into the path of the needle.

While, as stated above, the length of the prongs 83 and 84 may be varied somewhat, a specific example of an uncurler embodying this feature of the invention, which has been found exceptionally satisfactory for the purposes described, has been provided with a prong 84 which extends to a point about $\frac{1}{8}$ of an inch from the axis of reciprocation of the needle. This, in turn, is about $\frac{3}{32}$ of an inch in front of the point of tangency of the bite of the feed cup rims. The lower prong 83 in this example has been

made to extend slightly beyond the axis of reciprocation of the needle.

The construction shown in Figs. 1 to 12, inclusive, is adapted for the handling of hosiery blanks which when folded for seaming present an outside curl, as illustrated in Fig. 5. In Figs. 13 to 16 there is shown a modified form of the uncurler guide adapted for the performance of inside-out uncurling of the upper edge of the hosiery blank. It will be understood that the machine as a whole is the same as in the first embodiment and the difference between the two constructions is simply in the form of the work engaging portions of the uncurler. Thus the modified uncurler guide has a central support member 90, similar to member 70, provided with laterally extending ears at its lower end forming bearings for pivot pins 91 carried by clamping elements 92 and 93 having their upper ends yieldingly urged apart by a spring 94. To the lower end of the support member 90 there is also secured, by welding or the like, a center plate 95 along the opposite faces of which the work is drawn as it is advanced by the feed cups. Center plate 95 is of thicker construction than plate 72 of the first embodiment. It has a forwardly extending plough-like toe 96 and its upwardly and forwardly facing edge is preferably of scalloped configuration as indicated at 97. The forward end of the toe and the upper face of the extension are provided with a groove which presents surfaces 98 and 99 (Fig. 15) which slant downwardly and inwardly from the outer faces of the center plate toward its median plane. The form and disposition of these surfaces is such as to effect the desired inside-out uncurling action. The clamping elements have lower, forwardly extending boot portions 100 of the configuration best shown in Fig. 13, the inner faces of these portions conforming with the cooperating faces of the center plate. As best shown in Fig. 16, the center plate has outer faces, rearwardly of the toe 96, which are substantially flat and parallel back to the points designated 101 and from this point the outer faces are tapered inwardly at a small angle toward the rearmost extremity 102. A guide pin 103 is carried by the center plate in the same manner as the guide pin 81 of the first embodiment and cooperates with suitable openings in the clamping elements in a region at which the outer faces of these elements are sloped inwardly along the lines 104 (Fig. 16) toward the center plate. The rearward edge of the center plate is provided with a slot or channel 105 which extends downwardly and forwardly from its outer end, at a point substantially in line with the guide pin 103, to a point at its inner end which is below the guide pin. The lower edge of the slot is provided with a V-shaped groove which forms inwardly sloping surfaces meeting along a line 106 (Fig. 14) at the median plane of the center plate. This construction is such that the lower edge of the slot 105 will effect a second uncurling action upon the upper edge of the hosiery blank to offset any tendency of these edges to curl inwardly again in passing beneath the guide 103. Center plate 95 is provided with rearwardly extending prongs 107 and 108 which are similar to the prongs 83 and 84 of the first embodiment.

In the use of the modified form of uncurler, a hosiery blank 109, which may, for example, be of the looped toe type having its selvedges curled inwardly, as indicated at 110 (Fig. 13) is applied

to the uncurler guide in the position shown. It will be understood that the uncurler guide will have been shifted to its loading position when the new stocking blank is so applied to it. As the uncurler guide is shifted to its operative position the toe of the blank will be carried into the bite of the feed cups and the loop line 111 will be presented correctly to the stitch forming devices for the commencement of the overedge seam.

While the invention has been disclosed in considerable detail in relation to a preferred embodiment of the same and various modifications have been suggested, it will be understood that other modifications and adaptations of the invention may be made within the scope of the appended claims. Either of the forms of uncurler illustrated may be employed in the seaming of either looped toe or loopless toe hosiery blanks.

What I claim is:

1. In a sewing machine having a pair of horizontally disposed feed cups with cooperating rims for advancing work and stitch forming devices for producing overedge stitches in the region of the bite of the feed cups and above the upper edges thereof, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of said feed cups and another of said prongs being below said rims.
2. In a sewing machine having a pair of horizontally disposed feed cups with cooperating rims for advancing work and stitch forming devices for producing overedge stitches in the region of the bite of the feed cups and above the upper edges thereof, said stitch forming devices including a horizontally reciprocable needle, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of said feed cups and another of said prongs being below said rims, one of said prongs extending through the vertical plane containing said needle.
3. In a sewing machine having a pair of horizontally disposed feed cups with cooperating rims for advancing work and stitch forming devices for producing overedge stitches in the region of the bite of the feed cups and above the upper edges thereof, said stitch forming devices including a horizontally reciprocable needle, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of the feed cups and another of said prongs being below said rims, one of said prongs being above the upper edge of the rims

of said feed cups and another of said prongs being below said rims, said other of said prongs extending through the vertical plane containing said needle.

4. In a sewing machine having a pair of horizontally disposed feed cups with cooperating rims for advancing work and stitch forming devices for producing overedge stitches in the region of the bite of the feed cups and above the upper edges thereof, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of said feed cups and another of said prongs being below said rims, said prongs extending different distances from the rearmost edge of the main body of said center plate.

5. In a sewing machine having a pair of horizontally disposed feed cups with cooperating rims for advancing work and stitch forming devices for producing overedge stitches in the region of the bite of the feed cups and above the upper edges thereof, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of said feed cups and another of said prongs being below said rims, said center plate having uncurling edges extending upwardly and rearwardly from a point forwardly and below the upper edge of the uppermost of said prongs to a point above said prong.

6. In a sewing machine having a pair of horizontally disposed feed cups with cooperating rims for advancing work and stitch forming devices for producing overedge stitches in the region of the bite of the feed cups and above the upper edges thereof, the combination of a swingable uncurler guide arranged for swinging movement substantially in the vertical plane containing the line of feed through said feed cups, said guide having a center plate and a pair of work clamping elements for yieldingly urging the work against the opposite sides of said center plate, said center plate having forwardly extending surfaces arranged to uncurl inwardly rolled edges of said work and having additional surfaces adjacent the rearward edge of said plate for effecting a second uncurling action on said rolled edges of the work, and said plate having prongs projecting from the rearward edge thereof toward the bite of the feed cups, one of said prongs being above the upper edge of the rims of said feed cups and another of said prongs being below said rims.

7. In a sewing machine having a pair of horizontally disposed feed cups with cooperating rims for advancing work, stitch forming devices including a horizontally reciprocatory needle for forming over-edge stitches above said feed cups in the region of the bite thereof, the combination of a needle guard supported within one of said feed cups and extending over the upper

edge thereof, on both the work receiving and the work discharge side of said cups, said guard having a passage therein aligned with the path of reciprocation of the needle, a stitch finger positioned above said cups in the region of the bite thereof, a member mounted in the other of said feed cups for supporting said stitch finger, said member extending over the rim of said other cup forwardly and rearwardly of the path of said needle and having its outer end curved to conform with the curvature of said cup, and the upper edges of the curved end surfaces of said guard and said member being relieved in a region forwardly of the path of said needle to facilitate passage of the work into the bite of said feed cups.

8. In a sewing machine having a pair of horizontally disposed feed cups with cooperating rims for advancing work, stitch forming devices including a horizontally reciprocatory needle for forming overedge stitches above said feed cups in the region of the bite thereof, the combination of a stitch finger positioned above said cups in the region of the bite thereof, a member mounted within one of said cups for supporting said stitch finger, said member extending over the rim of said cup at least forwardly of the path of said needle and having its outer end curved to conform with the curvature of said cup, and the upper edge of said curved end surface being relieved in a region forwardly of the path of said needle to facilitate passage of the work into the bite of said feed cups.

9. In a sewing machine having a pair of horizontally disposed feed cups with cooperating rims for advancing work, stitch forming devices including a horizontally reciprocatory needle for forming over-edge stitches above said feed cups in the region of the bite thereof, the combination of a needle guard supported within one of said feed cups and extending over the upper edge thereof, on both the work receiving and the work discharge side of said cups, said guard having a passage therein aligned with the path of reciprocation of the needle, a stitch finger positioned above said cups in the region of the bite thereof, a member mounted in the other of said feed cups for supporting said stitch finger, said member extending over the rim of said other cup forwardly and rearwardly of the path of said needle and having its outer end curved to conform with the curvature of said cup, the upper edges of the curved end surfaces of said guard and said member being relieved in a region forwardly of the path of said needle to facilitate passage of the work into the bite of said feed cups, and a swingable uncurler guide arranged for swinging movement substantially in the vertical plane containing the line of feed through said feed cups, said guide having a center plate and a pair of work clamping elements for yieldingly urging the work against the opposite sides of said center plate, said plate having prongs projecting from the rearward edge thereof toward the bite of the feed cups, one of said prongs being above the upper edge of the rims of said feed cups and another of said prongs being below said rims.

10. In a sewing machine having a pair of horizontally disposed feed cups with cooperating rims for advancing work and stitch forming devices for producing overedge stitches in the region of the bite of the feed cups and above the upper edges thereof, the combination of a

swingable uncurler guide arranged for swinging movement substantially in the vertical plane containing the line of feed through said feed cups, said guide having a center plate and a pair of work clamping elements for yieldingly urging the work against the opposite sides of said center plate, said plate having a prong projecting from the rearward edge thereof toward the bite of the feed cups and beneath the work engaging rims thereof to a point rearwardly of the bite of said feed cups.

11. An uncurler guide for a sewing machine having a pair of feed cups which comprise a center plate disposed substantially in a plane tangent to the feed cups at the bite thereof, and a pair of clamping elements for retaining the work against the opposite faces of said plate, said center plate having a prong extending rearwardly to a point beyond the bite of said feed cups.

12. An uncurler guide for a sewing machine having a pair of feed cups which comprises a center plate disposed substantially in a plane tangent to the feed cups at the bite thereof, and a pair of clamping elements for retaining the work against the opposite faces of said plate, said center plate having a plurality of prongs extending rearwardly from the rearward edge thereof to points adjacent the bite of said feed cups.

13. An uncurler guide for a sewing machine having a pair of feed cups with cooperating work engaging rims which comprise a center plate disposed substantially in a plane tangent to the feed cups at the bite thereof, and a pair of clamping elements for retaining the work against the opposite faces of said plate, said center plate having a pair of prongs extending rearwardly from the rearward edge thereof to points adjacent the bite of said feed cups, one of said prongs being disposed at one side of said rims and the other at the opposite side thereof.

14. An uncurler guide for a sewing machine having a pair of feed cups with cooperating work engaging rims which comprises a center plate disposed substantially in a plane tangent to the feed cups at the bite thereof, and a pair of clamping elements for retaining the work against the opposite faces of said plate, said center plate having a pair of prongs extending rearwardly from the rearward edge thereof to points adjacent the bite of said feed cups, one of said prongs being disposed at one side of said rims and the other at the opposite side thereof, one of said prongs extending to a point on the discharge side of said feed cups.

15. An uncurler guide for a sewing machine having a pair of feed cups with horizontally disposed work engaging rims which comprises a center plate disposed substantially in a plane tangent to the feed cups at the bite thereof, and a pair of clamping elements for retaining the work against the opposite faces of said plate, said center plate having a pair of prongs extending rearwardly therefrom to points adjacent the bite of said feed cups, one of said prongs being disposed below the level of said rims and the other above the level of said rims.

16. An uncurler guide for a sewing machine having a pair of feed cups with horizontally disposed work engaging rims which comprises a center plate disposed substantially in a vertical plane tangent to the feed cups at the bite thereof, a work guiding pin projecting laterally from

said plate at each side thereof above said rims of the feed cups, and a pair of clamping elements for retaining the work against the opposite faces of said plate, said plate having prongs extending rearwardly therefrom toward the bite of the feed cups beyond the rearward edges of said clamping elements, one of said prongs being beneath the level of said rims and another being above the level of said rims.

10. 17. An uncurler guide for a sewing machine having a pair of feed cups with horizontally disposed work engaging rims which comprises a center plate disposed substantially in a vertical plane tangent to the feed cups at the bite thereof, a work guiding pin projecting laterally from said plate at each side thereof above said rims of the feed cups, and a pair of clamping elements for retaining the work against the opposite faces of said plate, said plate having prongs extending rearwardly therefrom toward the bite of the feed cups beyond the rearward edges of said clamping elements, one of said prongs being beneath the level of said rims and another being above the level of said rims, said prong above the level of said rims having its upper edge substantially at the level of the bottom of said guide pin.

18. An uncurler guide for a sewing machine having a pair of feed cups with horizontally disposed work engaging rims which comprises a center plate disposed substantially in a vertical plane tangent to the feed cups at the bite thereof, a work guiding pin projecting laterally from said plate at each side thereof above said rims of the feed cups, and a pair of clamping elements for retaining the work against the opposite faces of said plate, said plate having prongs extending rearwardly therefrom toward the bite of the feed cups beyond the rearward edges of said clamping elements, one of said prongs being beneath the level of said rims and another being above the level of said rims.

19. An uncurler guide for a sewing machine having a pair of feed cups with horizontally disposed work engaging rims which comprises a center plate disposed substantially in a vertical plane tangent to the feed cups at the bite thereof, a work guiding pin projecting laterally from said plate at each side thereof above said rims of the feed cups, and a pair of clamping elements for retaining the work against the opposite faces of said plate, said plate having prongs extending rearwardly therefrom toward the bite of the feed cups beyond the rearward edges of said clamping elements, one of said prongs being beneath the level of said rims and another being above the level of said rims.

20. An uncurler guide for a sewing machine having a pair of feed cups with horizontally disposed work engaging rims which comprises a center plate disposed substantially in a vertical plane tangent to the feed cups at the bite thereof, a work guiding pin projecting laterally from said plate at each side thereof above said rims of the feed cups, and a pair of clamping elements for retaining the work against the opposite faces of said plate, said plate having flat, substantially parallel faces on its two sides and said ele-

15

ments having forwardly extending inclined surfaces arranged to effect an outside-in uncurling action upon the upper edges of the work, said plate having prongs extending rearwardly therefrom toward the bite of the feed cups beyond the rearward edges of said clamping elements, one of said prongs being beneath the level of said rims and another being above the level of said rims.
